UNITED STATES PATENT OFFICE.

JAMES L. GALYEAN, OF WATERLOO, IOWA, ASSIGNOR TO WATERLOO CEMENT MACHINERY CORPORATION, OF WATERLOO, IOWA, A CORPORATION OF IOWA.

CONCRETE-MIXER.

1,161,304.

Specification of Letters Patent. Patented Nov. 23, 1915.

Application filed March 8, 1913. Serial No. 752,843.

To all whom it may concern:

Be it known that I, JAMES L. GALYEAN, a citizen of the United States, residing at Waterloo, in the county of Blackhawk and 5 State of Iowa, have invented certain new and useful Improvements in Concrete-Mixers, of which the following is a description.

My invention belongs to that general class 10 of devices known as concrete mixers or the like, and relates particularly to the type known as non-tilting batch mixers, and suitable discharging mechanism therefor.

The invention has among its objects the 15 production of a device of the kind described that is simple, convenient, durable, compact, efficient, and satisfactory, and that will not easily get out of repair or adjustment.

To this end my invention consists in the 20 novel construction, arrangement and combination of parts herein shown and described, and more particularly pointed out in the claims.

In the drawings, wherein like reference 25 characters indicate like or corresponding parts, Figure 1 is a sectional view of the mixing drum, showing my improved discharge mechanism applied thereto. Fig. 2 is substantially an end elevation of the same. 30 Fig. 3 is a detail view of the inner end of the discharging chute in inoperative position. Fig. 4 is substantially a sectional view taken on line 4, 4 of Fig. 1.

Referring to the drawings, 1 is a suitable 35 drum provided with ends 2 and 3, which have openings therethrough for charging at end 2 and discharging the mixture through end 3. As illustrated in the drawings, the complete mixing machine is not shown. Arranged at the discharging end of the drum is 40 a suitable frame, including the uprights 4 and 5, which are preferably secured or carried by the machine frame (not shown) carrying the mixing drum and the driving 45 means therefor. Secured to each of the uprights 4 and 5, are supporting plates 6' and 6, plate 6' being secured to the upright 4, and plate 6 to the upright 5. These plates 50 or supporting members carry or support the lower ends of links, which carry an adjustable chute or scoop 7. The scoop 7 is preferably formed substantially in the shape shown in the drawings, so that it may extend through and fit the opening in the dis- 55 charge end 3 of the drum, when in opera-

tive position, as indicated by the full lines in Fig. 1. When it is not desired to discharge the contents of the drum, the same is raised or thrown into the position indicated by the dotted lines in Fig. 1.

The scoop or chute 7 is pivotally or adjustably supported from the plates by the links 8 and 11, arranged at each side, the links 8 being somewhat shorter than the links 11, as shown in Fig. 1. The upper ends of the links 8 and 11 are pivotally secured at 9 and 12 to the scoop, and the lower ends at points 10 and 13 to the plates 6' and 6. The plates and ends of the links being arranged below the points 9 and 12, the weight of the scoop assists in maintaining the same in either position. The scoop is provided with a handle 14 upon one or both sides for convenience in operating the same.

A frame part or bracket 15 (see Figs. 3 75 and 4) is secured to the uprights 4 and 5, and extends under the scoop. Secured to the parts 15 is what may be termed a slop ring 16, which is formed with flange 17 extending into the drum. The slop ring prevents the concrete or mixture from slopping out around the chute through the discharge opening. It also serves as a rest for the inner end of the scoop when in inoperative position, as shown by the dotted lines in Fig. 1. The bracket also serves as a stop when the chute is thrown into operative position, 80 and the scoop, if desired, may be provided with a flange 18 arranged to coöperate therewith. The scoop may be locked in position 85 in any satisfactory manner. As shown, it is locked in inoperative position, or in mixing position, by a link or bar 19 secured to the plate 6 at 20, the movement of the same being limited by a slot and pin connection 90 at 26. The opposite end is provided with a notch 30 arranged to coöperate with the pin 29 on the chute 14. The weight of the arm or bar 19 tends to maintain it substantially 95 in the position shown in Fig. 1, and when the outer end of the chute is raised, the pin 30 on the chute throws the upper end of the bar toward the drum until the notch comes opposite the pin, at which time the bar falls over into engagement with the pin, locking 100 the chute substantially in the position shown by the dotted lines in Fig. 1. Means may also be provided for locking the chute in operative position, if desired, a bar or arm 19' being shown in the drawings, provided 105

110

with notch 30' and coöperating pin 29' on handle or chute. This bar is similarly connected at points 20' and 26'.

On the interior of the drum are preferably arranged a plurality of buckets 21 and 22, and for each bucket 21 is arranged a set or series of blades 23, 24 and 25. These blades are arranged in regular order, or stepped between the buckets, which are at 10 the discharge side of the drum, and the opposite end or charging end. If desired, there may be a series of blades for each bucket, but, I have shown them only for the alternate buckets 21. I have not considered 15 it necessary to illustrate the driving mechanism, nor the supporting frame for the drum. It may be mentioned, however, that a gear 28 may be arranged on the exterior of the drum, and the drum rotated by suitable gearing in mesh therewith. The drum may also be supported upon supporting rolls 27, and maintained in position in any desired way.

In operation, the drum is rotated in the 25 direction indicated by the arrow in Fig. 2, it being understood that the materials to be mixed are placed in the drum preferably through the charging opening in the end 2 in any suitable manner. The material is 30 mixed and partially lifted by the blades 23, 24 and 25, and carried to the buckets 21, some, of course, entering the buckets 22, by which it is lifted and dropped and mixed as long as desired. During the mixing operation, the discharge scoop or chute 7 is locked 35 in the position indicated by the dotted lines. When the mixture or concrete has been sufficiently mixed, and it is desired to discharge the same, the handles 14 are depressed, 40 throwing the scoop or chute into the position shown in Fig. 1 in the full lines. The material dropping from the buckets 21 and 22, falls into and is caught by the scoop or chute 7, and discharged into wheelbarrows, 45 or other suitable receptacles. As soon as the desired amount is removed from the mixing drum, the handles are raised, as previously described.

It may be mentioned that in a mixer constructed in this manner, the drum may be placed quite near the ground, so that the drum may be charged or discharged without the use of elevated platforms, or elevating mechanism of any kind. The mixer is rapid 55 in operation, and the discharge mechanism so simple that it practically cannot get out of order. It is easily operated, owing to the link connection described, the weight of the material assisting in operating the chute.

Having thus described my invention, it is 60 obvious that various immaterial modifications may be made in the same without de-

parting from the spirit of my invention; hence I do not wish to be understood as limiting myself to the exact form, construction, 65 arrangement, or combination of parts herein shown and described, or uses mentioned.

What I claim as new and desire to secure by Letters Patent is:—

1. In a device of the kind described and 70 in combination, an adjustable chute, and means for tiltably supporting said chute, including a fixed support and a plurality of links, each having one end pivotally secured to the chute and the other end pivotally secured to the support at a point below the chute.

2. In a device of the kind described and in combination, a tilttable chute, and means for supporting the same, comprising a fixed 80 support and a plurality of links, each having one end pivotally secured to the chute and the other end pivotally secured to the support, and a coöperating lock positioned below the chute and secured to said fixed 85 support.

3. In a device of the kind described and in combination, a tilttable chute, a supporting means therefor including a fixed support and a plurality of links arranged on 90 each side of said chute, and pivotally connected at their opposite ends to the chute and support respectively, a portion of said links of greater length than the others.

4. In a device of the kind described and 95 in combination, a movable chute and supporting means therefor, including a fixed support, a pair of links secured to said support and to the chute, a second pair of links of slightly greater length than said first 100 pair and pivotally secured to the chute and support, and means carried by said support for maintaining the chute in a tilted position.

5. A device of the kind described comprising the combination of a movable chute, supporting means therefor, including a stationary member carried by said fixed support, and a plurality of pairs of links arranged to pivotally connect the chute to said 110 support, one pair of links of slightly greater length than the other pair, and arranged with the shorter pair between said stationary support and the longer links, and a locking member carried by said fixed support for locking the chute in the desired 115 position.

In testimony whereof, I have hereunto signed my name in the presence of two subscribing witnesses.

JAMES L. GALYEAN.
